UNITED STATES PATENT OFFICE.

HARRY E. SOREF, OF MILWAUKEE, WISCONSIN.

COMBINED PADLOCK AND DOORBOLT.

Application filed February 17, 1923. Serial No. 619,623.

To all whom it may concern:

Be it known that I, HARRY E. SOREF, a citizen of the United States, and a resident of the city of Milwaukee, in the county of Milwaukee and State of Wisconsin, have invented certain new and useful Improvements in Combined Padlocks and Doorbolts; and I do declare the following to be a clear, exact, and complete description thereof, such 10 as will enable persons skilled in the art to which my invention relates to make and use the same, reference being had to the accompanying drawing as showing some forms of construction in which my invention has been embodied.

One of the purposes of the invention is the provision of a padlock which involves as an integral part of the construction thereof of a bolt, the invention being particularly 20 applicable to door fastenings of the hasp and staple type.

In my invention the post or shackle of the padlock is extended horizontally so as to constitute a locking bolt. The bolt is secured 25 in position upon the hasp so that the free end thereof may be entered into and withdrawn from the staple. When withdrawn, the padlock remains in fixed relation as a part of the hasp, and cannot be removed 30 therefrom when the door is opened. It results, therefore, that the lock is always in position for use when its service is needed.

The construction is best embodied in that 35 type of padlock in which the post or shackle is projected outwardly of the lock by means of a spring when the tumblers of the lock are operated so as to release the said post or shackle. In actual practice, the lock casing is retracted along the post or shackle, which latter does not change its 40 relative position with respect to the hasp to which the lock is secured.

Other details residing in the invention 45 will be specifically described, and the novelty of the whole will be pointed out in the appended claims.

Referring to the drawing:

Figure 1 is a view in elevation of the lock 50 in its operative position with the bolt thereof of engaging the staple.

Fig. 2 is a similar view showing the lock 55 as withdrawn or retracted upon the post or shackle, the lock casing being partially rotated upon its vertical axis so as to permit the withdrawal of the bolt from the staple as will be hereinafter described.

Fig. 3 is a vertical sectional view through the hasp and the bolt, on the line 3-3, Fig. 1, looking in the direction of the arrows, the lock casing being shown in full lines. 60

Fig. 4 is a longitudinal sectional view on the line 4-4, Fig. 2, looking in the direction of the arrows, showing the lock casing in full line position and also as having been partially rotated to the dotted line position 65 to permit the withdrawal of the bolt.

Fig. 5 is a modification of the construction, in which the necessity for partial rotation of the lock casing to permit the withdrawal of the bolt from the staple is obviated. 70

Fig. 6 is a vertical sectional view on the line 6-6, Fig. 5, looking in the direction of the arrows, the lock casing being shown in full lines. 75

Fig. 7 is a horizontal sectional view on the line 7-7, Fig. 5, looking in the direction of the arrows, and showing the squared construction of the post or shackle of the lock, whereby rotation of the lock casing may not 80 be effected.

In the drawing, the numeral 10 indicates a hasp hinged as at 11 to a plate 12, which latter will be secured to the free edge of a swinging door, the fastening screws passing 85 through the plate 12, being concealed by the hasp 10. The numeral 13 indicates a plate which may be attached to the face of the door casing, by screws which are concealed by the hasp when the locking operation has 90 been effected.

The casing 14 may embody a lock mechanism of any appropriate construction, which is operated by a key 15 in the usual manner. The post or shackle 16 is secured in the lock 95 casing as usual. The lock casing 14 is adapted to have a limited movement along the post or shackle under the influence of a spring when the tumblers of the lock are operated by a key. 100

The upper end of the post or shackle is formed as a bolt 17, which in the constructions illustrated, extends at a right angle to the axis of the post or shackle. The said bolt is guided by a housing 18, secured upon the hasp 10. An annular shoulder 19 is formed upon a bolt near the point of its juncture with the post or shackle and by engagement with the rear end of the housing 18, serves as a stop to limit the outward 110 movement of the bolt. A stop 20, which may be conveniently formed by punching

out a portion of the plate forming the hasp, arrests the rearward movement of the bolt, by engaging the post or shackle near the point of its juncture with the bolt. A staple 21 secured upon the plate 13 passes through an elongated opening 22 formed in the hasp, when the free end of the hasp is swung into engagement with the said plate 13. With the parts in such position, the bolt may be moved forwardly through the housing 18, so that the free end thereof will engage with the staple so as to prevent separation of the hasp from its engagement with the plate 13 or the relative movement of the parts to which these elements are connected. The stop 20 is formed upon the hasp 14 at a distance sufficient to arrest the rearward movement of the bolt when the free end thereof has been withdrawn from the staple, so that the hasp is free from restraint as the door is opened.

The housing 18 for the bolt is cut away on a transverse line so as to provide a clearance 23 for a purpose to be described. The bolt 17 is provided with a bore or depression 24, which is adapted to be entered by the free end of a pin or stud 25, set in fixed position in the lock casing, and extending parallel to the post or shackle 16. When the bolt 17 is moved outwardly to engage the staple, and the annular rib 19 is brought into engagement with the rear end of the housing 18, the bore 24 in the bolt will be exposed through the clearance 23 in the casing. By aligning the longitudinal vertical central plane of the lock casing in parallelism with the axis of the bolt, the pin or stud 25 may be made to pass through the clearance 23 and engage the bore 24 in the bolt, by movement of the lock casing on the post or shackle by pressure against the force of the spring which is employed to give relative movement to the lock casing 14 of the post or shackle 16.

The tumblers of the lock then act to hold the casing and the post or shackle in set position.

Upon withdrawing the tumblers through the medium of the key 15, the pin or stud 25 is withdrawn from its engagement with the bore 24 in the bolt and the lock casing may be partially rotated upon the post or shackle 16 so as to swing the said pin or stud out of the clearance 23 in the housing 18. Thereafter the bolt may be moved backwardly so as to withdraw the free end thereof from engagement with the staple. As before stated, the stop 20 arrests a backward movement of the bolt when the end thereof has cleared the staple 21. Thus the lock cannot be detached from the door while in its inoperative position.

When it is desired to lock the door, it is necessary only to pass the hasp over the staple, and slide the bolt into locking position.

The lock casing is then given a partial rotation in return so as to enter the pin or stud 25 in the clearance 23. Whereupon the said pin or stud will engage the bolt as before described, and the locking operation is completed.

Fig. 5 shows a modification of the invention in which the construction is somewhat simplified. The hasp 10, the pivoted plate 12, the plate 13, and the housing 18 are as before described. In this construction the transverse bore 24 in the bolt is omitted. The post or shackle 161 is squared, and slides in a correspondingly shaped opening in the lock casing 141. The pin or stud 251 is set in the lock casing as in the previous construction. However, the free end of the said pin or stud is adapted merely to engage the walls of the clearance 23 formed transversely of the casing 18, when the parts are in the operating position illustrated in Fig. 5. The retractive movement of the casing 141 along the post or shackle will withdraw the pin 251 from the engagement described, the end of the pin then clearing the housing, sufficiently to permit the bolt to be moved from its position of engagement with the staple 21. The extent of movement of the lock casing to withdraw the pin 251, and permit longitudinal movement of the bolt is indicated by the dotted line position of the lock at the lower part of Fig. 5.

In either construction, with the pin or stud 25 entered in the transverse bore in the locking bolt, or the squared shank of the post or shackle fitting its correspondingly shaped guide-way, the lock casing cannot be rotated about the post or shackle to free the bolt when locked. In practice, the clearance 23 will have such circumferential extent about the bolt housing 18, that my improved locking device is readily applicable to doors opening either right or left.

Although I have shown my invention in some simple constructional forms, it is to be understood that the construction may be varied in some of the details without departing from the spirit of my invention or the scope of my claims. The gist of the invention resides in the construction of a padlock having a bolt formed integrally with the post or shackle of the lock, and movable into and out of operating position.

Having thus described my invention, what I claim and desire to secure by Letters Patent of the United States, is:

1. In a locking device, a sliding bolt, means for guiding the same, a lock casing having a post or shackle connected to the bolt, and means on the lock casing for engaging the guiding means to retain the bolt in locking position.

2. In a locking device, a sliding bolt, means for guiding the same, a lock casing

having a longitudinally movable post or shackle connected to the bolt, and means on the lock casing for retaining the bolt in locking position.

5. 3. In a locking device, a sliding bolt, means for guiding the same, a lock casing having a longitudinally movable post or shackle directly connected to the bolt, and means for holding the bolt in locked position.

10. 4. In a locking device, a lock casing, a post or shackle movable therein, a locking bolt integrally formed with the post or shackle and extending at an angle thereto, 15 in combination with a guide for the bolt, and means on the lock casing for engaging the guiding means to hold the bolt in locked position.

5. In a locking device, a lock casing, a post 20 or shackle longitudinally movable therein, a locking bolt integrally formed with the post or shackle and extending angularly therefrom, in combination with a guide for the bolt, and means for holding the bolt in 25 locked position.

6. In a locking device, a sliding bolt, means for guiding the same, a lock casing provided with a post or shackle formed integrally with the said bolt, a pin or stud 30 on the lock casing, the said guiding means being provided with a clearance in which the pin enters to hold the bolt in locking position.

7. In a locking device, a sliding bolt, means for guiding the same, a lock casing 35 provided with a post or shackle formed integrally with the said bolt, a pin or stud on the lock casing, the said guiding means being provided with a clearance in which the pin enters to hold the bolt in locking position, and a stop to prevent removal of the bolt from its guiding means.

8. In a locking device, a hasp, a bolt and guiding means on the hasp for the bolt, a lock casing having a post or shackle connected to the bolt, and means on the lock casing for engaging the said guiding means for retaining the bolt in locking position upon the hasp.

9. In a locking device, a hasp, a bolt, and 50 guiding means on the hasp for the bolt, a lock casing having a post or shackle connected to the bolt, means on the lock casing for engaging the said guiding means for retaining the bolt in locking position, and 55 means to prevent removal of the bolt from its guiding means when in unlocked position.

In testimony whereof, I have signed my name at Milwaukee, this 5th day of February, 1923.

HARRY E. SOREF.
